VENDING MACHINE FOR PENCILS OR THE LIKE

Harold M. Schaef, 5711 W. Grand Ave., Chicago, Ill.

Filed Mar. 7, 1960, Ser. No. 59,634

Term of patent 14 years

(Cl. D52—3)

Fig. 1.

Fig. 3

Fig. 2.

FIG. 1 is a front perspective view of a vending machine for pencils or the like embodying my new design. FIG. 2 is a front view thereof.

FIG. 3 is a sectional view of the front panel of the machine, taken substantially on line 3—3 of FIG. 2.

The undisclosed side of the vending machine is substantially the same in appearance as the side shown, and the rear is plain.

The vertical lines on the face panel represent contrasting color areas.

I claim:

The ornamental design for a vending machine for pencils or the like, substantially as shown and described.
